UNITED STATES PATENT OFFICE

FRANK C. REILLY, OF NEW YORK, N. Y.

LIQUID IDENTIFICATION

Application filed March 10, 1928. Serial No. 260,721.

This invention relates to the identification of more or less liquid substances, such, for instance, as lubricating oils.

The objects of the invention are to mark the oil or other material in such a way that it may be readily and positively identified and to accomplish this without impairing the qualities or in any way limiting the usefulness of the material.

10 In one practical and preferred example of the invention, lubricating oil such as customarily supplied to motorists is identified and made recognizable to the users of the same by small markers such as letters, initials 15 or arbitrary symbols of about the same specific gravity as the oil so as to remain in suspension therein and flow freely in the pouring of the oil. These characters intermingle and distribute themselves more or less 20 evenly throughout the oil without settling or on the other hand, floating to the surface and may be of such a nature as to dissolve and add certain lubricating qualities to the oil under the influence of a definite rise in temperature.

In the accompanying drawing, practical embodiments of the invention are illustrated.

Thus, in Figure 1, letter symbols supplying the trade name of the oil are mixed in 30 the oil so as to pour freely therewith.

Figures 2, 3 and 4 are detail views illustrating other forms of identifying characters.

In Figure 1, numerous letter symbols 5 are shown, formed of some suitable oily or other 35 material, which with heat will become soluble in the body of oil 6. These letter symbols may supply the name, trade-mark, grade or otherwise identify the oil and while naturally they will not arrange themselves in the order to 40 supply the trade name, grade or other identifying characteristic, they will be selected with a view to affording the desired identification, even in their more or less "jumbled" state.

45 In the illustration just considered, six different letters are employed to supply the entire word, but if desired, only letters forming the initials or certain striking letters in the word may be selected.

50 For example, in Figure 2, symbols in the

form of circular figures 7 may be used. Figure 3 illustrates the use of star shaped identifying characters 8 and Figure 4 illustrates a fanciful character 9 made up of a combination of two letters.

35

The identifying symbols may have a natural color or be colored artificially to make them stand out in the liquid and they may be placed in the liquid at the time of manufacture or subsequently, for instance, at a time when the liquid is packaged by the manufacturer or distributor.

60

The composition and specific gravity of the identifying characters will vary, depending upon the fluids in which they are used 65 and they may be given characteristics for improving the quality of the fluid or for qualifying it in some other way. For example, in the case of fluids such as table syrups, the identifying characters may be made of sugary 70 material, spiced or flavored to give zest to the product, and in the case of lubricating oils, the identifying characters may be of an oily, greasy or similar material or materials for preventing carbon formation.

75

What is claimed is:

As a new article of manufacture, means for identifying a liquid, comprising readable characters having a selected definite significance designating origin or other desired 80 characteristic or quality of the liquid, said characters being of a material having a specific gravity so related to that of the liquid as to float in a state of suspension in the body 85 of liquid and be thereby distributed substantially uniformly throughout the liquid, said identifying characters being soluble in the enveloping liquid under influence of heat.

85

In witness whereof, I have hereunto set my hand this 20th day of January, 1927.

90

FRANK C. REILLY.
